(57) CLAIM

The ornamental design for a purse organizer with water holder, as shown and described.

DESCRIPTION

FIG. 1 is a front, right side, top perspective view of a purse organizer with water holder showing my new design; FIG. 2 is a rear, left side, bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is a front, right side, top perspective view of the purse organizer with water holder when one of the components of the purse organizer with water holder is removed from the purse organizer with water holder. The broken lines depict portions of the purse organizer with water holder that form no part of the claimed design.
